[57] CLAIM

The ornamental design for a tape transport, substantially as shown and described.

DESCRIPTION

FIG. 1 is a front and right side perspective view of a tape transport showing my new design;

FIG. 2 is a right side elevational view, the left side being a mirror image thereof; and

FIG. 3 is a rear elevational view thereof.

The conventional electrical cord has been shown fragmentarily in FIG. 3 for convenience of illustration.

FIG_1

FIG. 2

FIG. 3
